L. J. STONE

MEANS FOR SECURING DOWELS, TENONS, ETC., IN MORTISES

Filed Mar. 26, 1921

Inventor:
Leo J. Stone,
By his Attorney, Leo. W. McAffy

UNITED STATES PATENT OFFICE.

LEO J. STONE, OF BROOKLYN, NEW YORK.

MEANS FOR SECURING DOWELS, TENONS, ETC., IN MORTISES.

Application filed March 26, 1921. Serial No. 455,908.

To all whom it may concern:

Be it known that I, LEO J. STONE, a citizen of the United States, residing in the borough of Brooklyn, county of Kings, city and State of New York, have invented certain new and useful Improvements in Means for Securing Dowels, Tenons, Etc., in Mortises, of which the following is a specification.

10 My invention is designed to afford a simple, inexpensive mechanical expedient whereby wooden or similar compressible tenons, dowels, etc., may be positively clinched and locked in the mortises formed for their 15 reception, superseding or supplementing the usual method of gluing or cementing such male parts within their mortises.

While utilizable in conjunction with mortise joints generally, my clincher-insert is 20 especially efficacious and adaptable for use in the manufacture of furniture, or for analogous purposes of construction and manufacture where shrinkage of tenon or dowel is liable to occur, resultant from long 25 use, climatic conditions, the deterioration of glue or cement heretofore relied upon as binding means, undue strain, and various other reasons.

My invention consists essentially of a 30 mortise insert formed with a base adapted to contact with the sides of the mortise for which it is provided, and to centralize and maintain the alignment of the wedge part of the insert in such manner that a portion 35 of a dowel or tenon of wood or other compressible material forced into the mortise will be split, spread and compacted into rigid contactual engagement with the sides of said mortise, thereby practically clinching the 40 tenon or dowel within its mortise, as and for the purposes herein set forth.

In the accompanying drawings,

Fig. 1, is a perspective view of a mortise insert made in accordance with my invention;

Fig. 2, is a top view thereof;

Fig. 3, is a view of the under side thereof;

Fig. 4, is an edge elevation thereof;

Fig. 5, is an edge elevation thereof taken 50 at right angles to Fig. 4;

Fig. 6, is a top view of the insert showing a modification of base construction thereof;

Fig. 7, is a sectional view showing the

use of my mortise insert as a means of securing a dowel pin in mortises formed in 55 superposed parts to be united thereby;

Fig. 8, is a top view of a clincher insert having a base formed to fit in a square tenon mortise;

Fig. 9, is a similar view of a clincher insert having a base adapted to fit in an elongate rectangular tenon mortise;

Fig. 10, is a sectional view showing my clincher insert as applied to a tenon mortise;

Fig. 11, is a top view of a modification in 65 the structure of my clincher insert;

Fig. 12, is an edge elevation of the clincher insert shown in Fig. 11.

My clincher insert C, is preferably metallic, and is designed primarily, of course, for 70 use in connection with wooden material, although available wherever a tenon or dowel of compressible character is employed in effecting a mortise joint, whether the mortise be formed in compressible material, or, relatively speaking, in non-compressible material. That is to say, my clincher insert C, may be used in a metallic socket, provided 75 the tenon T, or dowel D, to be secured therein is penetrable and compressible so as to 80 function as herein described.

A distinctive feature of my clincher insert C, is its spacer-base b, adapted to fit, in whole or in part, the cross section of the mortise m, for which it is designed. In other 85 words, the main function of the base b, is to space from the mortise walls and centralize the wedge w, as related to the medial area of the mortise m, into which my clincher-insert C, is inserted; and this it does by contacting with the side walls of the mortise m, in such manner as to obviate any possibility 90 of looseness or play of the insert therein. Thus, if the mortise m, is cylindrical in shape, obviously a round base b, as shown in 95

the first five figures of the drawings will answer the purpose; or a like result may be attained by a base b, formed with bearing edges b', as indicated in Figs. 6 and 12, for instance, in which provision is made for so 100 contacting with the inner side walls of the mortise m, as to insure the axial alignment of the wedge w, as related to the center of the mortise. Thus, in the construction of base b, shown in Fig. 6, the ends b', b', of 105 the four radial portions thereof will insure

a proper spacing fit of the clincher insert in a cylindrical mortise, as will also the peripherally segmental portions b' , b' , of the base b , shown in Fig. 11. Or in the case of a 5 square or oblong rectangular mortise for a tenon T, of like configuration an essentially square or oblong rectangular base b , such as indicated in Figs. 8 and 9, will answer the purpose.

10 In any case, as before intimated, the main function of the base b , is to centralize and sustain the wedge w , in the mortise m , so that the edge e , of said wedge w , will contact medially with the end of a tenon T, or 15 dowel D, inserted in the mortise, as the case may be.

The edge e , of the wedge w , is made sharp and chisel-like to facilitate penetration into the opposed end of a tenon T, or dowel D, so 20 that the act of forcing the said tenon T, or dowel D, into the mortise results in the splitting of said impinging end of the tenon or dowel in such manner that the inclined surfaces of the wedge w , will compress and 25 clinch the bifurcations of tenon or dowel, thus formed, forcibly and positively against the inner side walls of said mortise, thereby securely and permanently locking the copulated parts together.

30 It will be seen from the foregoing description that my clincher insert for mortises may be employed advantageously not only in the construction of furniture, but also that the essential features of my invention are adaptable to wooden structural work 35

generally, so that I do not limit myself in this particular.

What I claim as my invention and desire to secure by Letters Patent is,

1. As an article of manufacture, a mortise 40 insert comprising a metallic wedge formed with a base adapted to snugly fit a mortise to centralize the wedge with reference to the mortise, for use with a compressible dowel or tenon to initially split and then compress 45 and tighten the dowel or tenon forced into the mortise, whereby the dowel or tenon is held against outward movement by the direct frictional contact of the compressed portion thereof with the walls of the mor- 50 tise.

2. In a joint, the combination of a member provided with a projecting compressible tenon, a member provided with a mortise snugly receiving said tenon, and a mortise 55 insert having a base snugly fitting said mortise to centralize the insert with reference to the mortise, the said insert having a sharpened edge penetrating, spreading and localizing said tenon and compressing the latter 60 against the walls of the mortise, whereby the tenon is held against outward movement by the direct frictional contact of the compressed portion thereof with the walls of the mortise.

LEO J. STONE.
